Specification of Letters Patent.

Patented Jan. 2, 1912.

Application filed February 18, 1911. Serial No. 609,455.

To all whom it may concern:

Be it known that I, WILLIAM E. SHARP, a citizen of the United States, residing at Chicago, in the county of Cook and State of Illinois, (whose post-office address is 5528 South Sangamon street, Chicago, Illinois,) have invented new and useful Improvements in Heaters, of which the following is a specification.

10 This invention relates to certain improvements in heaters in which the heating agent is a liquid capable of being vaporized, the vapor being generated by heat, so that the volatile element or elements of the liquid pass to the burner in the form of a gas. Many liquids are capable of being volatilized by heat, and while my invention is applicable to liquid hydro-carbons generally, it is particularly designed to use denatured 20 alcohol as the fuel agent, and in some instances gases.

My invention relates more particularly to means for automatically controlling the supply of liquid and gaseous fuel, and the specific embodiment in which I have chosen to illustrate my invention in the accompanying drawings comprises a liquid supply pipe, a vaporizing conduit to which the liquid fuel is delivered, a distributing rod or core with 30 in the conduit, a valve arranged in the coupling between the supply pipe and a volatilizing expansion tube forming a portion of the conduit and controlled by the expansion of such tube, the liquid fuel being delivered 35 into the conduit in which the vaporization is completed and all particles of carbon arrested, a coupling member being in connection with said conduit and having a jet orifice arranged in line with a mixing tube. 40 in which the gas is mixed with air, and a burner to which the gas is delivered. Such burner has tips or jets so located as to heat the vaporizing members, the valve being located outside of the zone of heat and operated by the expansion of the heated vaporizing tube. Incidental to these features above, I provide in the combined carbon-arrester and secondary vaporizing chamber fragments of material, such as shot, preferably 45 loose, which check and collect all particles 50 of carbon coming over with the gas from

the vaporizing expansion tube and by their movement prevent caking. I also provide a priming pan to contain a sufficient quantity of fuel to preliminarily heat the parts, this 55 being rendered necessary by the fact that burners consuming liquid fuel, such for example as alcohol, require an initial heating in order to produce the vaporization or volatilization of the liquid constituting the 60 heating agent. I also provide various necessary or desirable means for adjusting the parts.

In burners of this kind it has been usual to pass the liquid fuel into a feed tube so 65 placed as to be heated by the combustion at the burner, whereby the liquid passing through such tube is volatilized or converted into a gas, and to place centrally within such tube a distributing core or member so 70 that the liquid is reduced to a relatively thin body surrounding the core and in contact with the inner surface of the heating tube. If the space between the core and tube is made small enough to limit the quantity of 75 passing liquid so as to supply the burner with a normal amount of fuel only, or in other words, to constitute in and of itself a regulator of the fuel supply, it must be made so small that it is likely to become 80 clogged or choked with a deposit of carbon and to interfere with the uniformity of the supply, if not cut it off completely. On the other hand, if the space or passage is made large enough to avoid this difficulty, then an 85 excessive quantity of the liquid will be supplied and vaporized, thus creating a gaseous pressure sufficient to produce a reaction which will extinguish the flames of the burner. In other words, the pressure is likely to 90 fluctuate sufficiently to temporarily cut off the supply of gas to the burner, thereby extinguishing the flames. These difficulties are serious, particularly when the burners are used to heat railway cars, warehouses, 95 or the like, for the preservation of perishable commodities such as fruits and vegetables, because the value and efficiency of the device depends almost wholly upon its indefinite and uninterrupted operation without attention.

One of the leading objects of my inven-

tion is, therefore, to produce a device of this character which shall operate indefinitely under automatic control.

Another object of the invention is to afford an automatically-governed burner which, after being properly adjusted by the manufacturer, is practically proof against derangement by inexperienced persons; and to that end my apparatus is so constructed as to make its controlling parts practically inaccessible without dismembering the apparatus itself.

Other features of novelty and improvement will be pointed out in connection with the following detailed description of the apparatus and in the claims.

In the drawings Figure 1 is a plan view of a burner and its accessories embodying this invention; Fig. 2 is a longitudinal, central, vertical, sectional view on line 2—2 of Fig. 1; and Fig. 3 is a cross section on line 3—3 of Fig. 1.

The burner 32 is in the form of a hollow, annular body having a plurality of upwardly standing burner tips 33, apertured to provide orifices through which the gas issues to be burned. A main vaporizing or volatilizing expansion tube 34, preferably of brass, is held on top of the burner 32 by a strap 35, one end of such tube carrying a threaded collar 36, brazed or otherwise fixed thereon and affording an abutment for one member 37 of a divided valve-casing screwed on the threaded end of the tube. The outer end of such valve-casing member 37 is internally screw-threaded, and is adapted to accommodate the reduced threaded portion 38 of a coupling member 39, the latter having an annular shoulder 40 adapted, when the parts are properly screwed together, to bear against the casing 37. The outer end of the member 39 is constructed for connection with a feed pipe 41, which will be connected with a fuel reservoir (not shown). The member 39 has a central valve port 42, and an annular, slightly-beveled valve-seat 43. A spherical valve 44 fixed to or forming a part of a non-expansive metal rod 45, is arranged centrally within the tube 34, the outer face of the valve having a nick or slot 46 for the application of a screw driver or other tool for the adjustment of the valve. The non-expansive metal of which rod 45 is composed is preferably of metal known as "Invar."

The inner end of the vaporizing expansion tube 34 is screw-threaded into an end wall of a hollow, cylindrical, cast-brass, combined carbon-collecting and supplementary liquid-volatilizing chamber 47, a fixed shoulder or collar 48 on the tube limiting its movement and definitely determining the length of exposed tube between the parts 37 and 47. This secondary-vaporizing and sediment-arresting member 47 is preferably

substantially filled with loose shot, which act as a carbon-collecting medium and as a distributing core. At its top such relatively large shot-filled chamber has a tubular extension 50 through which the shot or other small particles may be inserted or removed, and on top of the part 50, or in any other suitable manner, is removably fastened a deflector 51 which acts to direct the heat from some of the adjacent flames downwardly upon the member 47 and to distribute the heat substantially-uniformly over its surface.

A section of pipe 52 is secured to the burner by means of a clamp 53, the inner end of such pipe being threaded into the opposite end wall of the chamber 47 to an extent permitted by a shoulder 54. The tube 52, as is illustrated, is in alignment with the tube 34, and on its outer end is secured a coupling member 56, preferably a casting, definitely positioned on the tube by a limiting collar or abutment 55. This coupling member has a cavity 57 which communicates with a vertical passage 58, the latter in turn communicating with a lower horizontal passage 59 having a gas discharge opening or outlet 60. The ends of the two intersecting passages 58 and 59 are closed as shown by screw plugs 61 and 62.

64 is a tubular mixing chamber, supported beneath the burner and communicating with the interior of the same through an aperture 63, air being supplied through the opening or space 65 between the inlet 60 and the open end of the mixing chamber 64.

A shallow pan 66 beneath the burner proper is adapted to hold a sufficient quantity of combustible fluid to effect a preliminary heating of the burner and vaporizing elements to establish the volatilization of the liquid fuel for the permanent support of combustion. The end of the non-expanding rod 45 opposite the valve 44 is preferably screwed into a threaded cavity 67 in coupling member 56, in alignment with the axis of the tubes 52 and 34. In order to secure and maintain the proper relation between the spherical valve 44 and its co-operating valve seat 43, so that the expansive action of the tube 34, due to the heat of a pair of normal flames at the two jet orifices 69 located in close proximity to the sides of the tube, will open the valve an amount only sufficient to permit a feeding of the liquid fuel for the maintenance of a normal flame at the burner, all of the parts are screwed home or brought against their coacting shoulders, with the exception of the pipe 41, and then by means of a screw driver fitted in the socket 46 and projected through the member 38 the valve 44 and rod 45 are turned back so as to bring the valve securely against the seat 43, in which position it can be tested to determine whether

the contact is proper and effective. When such test indicates that the valve bears properly on its seat, a hole is drilled through the member 56 and the end of the rod 45, 5 and a pin 68 driven into such hole thereby preventing any further or subsequent adjustment or manipulation except upon the removal of the pin and the uncoupling of the valve-casing. By this means assurance 10 is given that if the valve member 39 is screwed up so that its shoulder 40 engages the member 37, the port 42 will be completely closed by the valve 44 when the burner is out of operation.

15 From the foregoing description it will be seen that the several parts of the device are of such construction as to permit of their being accurately positioned and definitely set by the maker after proper test, 20 and that after adjustment the device is automatic in its operation and incapable of being tampered with or put out of adjustment. Such preliminary test and adjustment having been made and the several parts 25 being proportioned with reference to the expansibility of the member 34, together with the relatively small expansion of parts 47, and 52, and the non-expansibility of the member 45, it is obvious that during the 30 normal operation of the burner the valve will be open, due to the expansion of the tube 34, chamber 47 and tube 52 under the influence of the heat, and the degree of opening may be absolutely determined and 35 maintained because the valve itself is located beyond and so far removed from the zone of vaporization or volatilization that it will not be clogged by a deposit of carbon in the valve opening. The liquid after 40 passing the valve reaches and passes through the vaporizing tube 34, which, being heated, causes the volatilization of the liquid, the gas then passing into the carbon-collecting chamber 47 which also acts as a secondary or 45 assistant-vaporizing member. This chamber having a wall of considerable thickness and being subjected to the deflected heat of the flames of a portion of the burner tips, becomes heated and elongated slightly as 50 compared with the expansion of tube 34; and if any of the fuel agent or alcohol passes into such chamber 47 in liquid form its vaporization will be completed therein, while the particles of carbon will be arrested and collected by the shot, the movement of which when the burner is mounted on a vehicle such as a railway car will prevent clogging, while the shot also acts to 55 fractionate or break up the gas in its flow through the chamber. From this chamber the gas flows through the tube 52 and passages 57 and 58, issuing with considerable force through the restricted orifice 60, thus preventing any flame or back burning at 60 this point. It should be noticed that the

parts 34, 47 and 52 in combination form an expandible vaporizing conduit, the greater portion of the vaporization and expansion occurring in tube 34. The gas mingled with air entrained or admitted at 70 the open port 65, enters the mixing chamber 64 and is thoroughly mixed before it reaches the burner cavity. The passage of the gas and air through such chamber 64 is sufficiently rapid to prevent maintaining 75 any burning or flame therein, so that it is impossible for a burner of this kind to burn back either at the orifice 60 or in the mixing chamber.

If for any reason the flame of the burner 80 becomes extinguished, the tube 34, chamber 47, and tube 52 will contract, and the valve coming in contact with its seat will shut off the supply of liquid fuel. The heated chamber 47 acts in conjunction with the 85 vaporizing expansion tube 34 to assist in the regulation of the flow of liquid. That is, it cares for the slight irregularities in the action of the valve 44. For example: If a slightly excess quantity of liquid 90 passed the valve 44, it would be vaporized in the parts 34 and 47, creating a sufficient excess pressure therein to tend to force back the further flow of fuel through the valve. In other words, the member 47 acts as a 95 supplementary vaporizer and fluid fuel feed governor as well as a carbon collector. This chamber 47 being in cross section considerably larger than the tubes 34 and 52, provides adequate space for the collection 100 and arresting of any carbon particles which may enter the same with the gas.

My apparatus, it will be observed, dispenses entirely with manually operated valves. It will be noted, also, that my automatic regulating apparatus combines the supply tube with the volatilizing chamber and that this latter carries one member of the valve and therefore constitutes an essential element of the regulator itself, 110 while the other member of the valve is mounted upon a rod which forms the central core of the volatilizing chamber, the whole constituting a valve-controlled passage between the supply pipe and the burner. 115

In the above I have referred to the expansion of tube 34 as controlling the opening and closing of the valve; and in this connection it might be remarked that none of the other parts of the burner are sufficiently heated to affect the operation of the valve in any substantial or material degree. Deflector 51 acts to equalize the heat imposed upon the chamber 47, consequently securing an efficient and uniform vaporization of any of the fuel which may enter the compartment in liquid form, which could not result if the flames played directly on this part.

I am aware that it has been proposed to 130

control the admission, to regulate the supply and to cut off the flow of hydrocarbon fluid to a vapor burner and that it is common to employ in such means a thermostatic device, 5 the thermostatic elements usually of two or more members having different coefficients of expansion, the regulation being due to this difference in the expansion of the elements. My invention is distinguished by 10 the fact that it involves a single thermostatic element, to wit, the tube carrying a valve member, and the other valve member is carried by a non-expansible rod so that the valve member carried by the rod after 15 being adjusted to afford the requisite degree of opening, when the expansible member is expanded to its limit, remains fixed or stationary relative thereto. Thus the expansible member serves first to open the 20 port to its widest extent when expanded to its limit and consequently maintains the valve in the open position during the normal action of the burner, and when the flame is extinguished rapidly contracts, thus serving 25 to cut off entirely the supply. Thus a single thermostatic element operates first as a valve opener, second as a regulator and third as a cut-off. The advantage of this construction having a single expansible element over 30 those having two or more expansible elements is that it is impossible, under practical conditions of service, to first determine and then maintain regulation under the variations of expansion occurring between the 35 two related elements, while with a single expanding element its movement may be calculated and determined, and when the valve is once adjusted with reference thereto the regulation is not only automatic but it is 40 reliable.

I claim:

1. In an alcohol burner, the combination with a burner cap of means for furnishing a uniform supply of combustible gas to the 45 burner to maintain a normal flame, said means comprising a supply pipe provided with a valve member, a vaporizing tube connected with the supply pipe around the valve member and arranged in proximity 50 to the burner and composed of a metal having a high coefficient of expansion, a rod secured within the tube and provided with a valve member, said rod being composed of a material which is non-expansive, and said 55 tube serving as a vaporizer, a conduit for the generated gas and as a thermostatic element, and in connection with the valve member fixed in relation thereto and said first-mentioned valve member constituting the 60 sole means for admitting, regulating and shutting off the supply of liquid fuel, and connections between the delivery end of said tube and the burner to deliver the gas, substantially as described.

2. In a device of the character described,

the combination of a burner, a vaporizing expansion tube subjected to the heat of the burner, a chamber member connected to said tube and forming therewith a conduit for the passage of a fluid fuel for said burner, a 70 distributing rod secured in said tube and chamber, and loose deposit-collector members in said chamber around said rod, and means controlled by the relative expansion and contraction of said conduit and rod to 75 govern the flow of fuel through said conduit to the burner, substantially as described.

3. In a device of the character described, the combination of a burner, a vaporizing tube, a chambered member in connection 80 with said tube and forming therewith a portion of the conduit subjected to the heat of the burner and acting as a passage for a fluid fuel for said burner, a distributing rod extended through said tube and chamber, 85 loose distributing members in said chamber surrounding said rod, and means to control the flow of fuel through said tube and chamber comprising a member with a valve-seat and port, and a valve on said rod coöperating 90 with said seat, the lengths and coefficients of expansion of said tube and rod being such that the valve and the valve-seat will be separated by the expansion of the conduit due to a normal flame at the burner 95 an amount sufficient only to maintain such normal flame at the burner, whereby said valve acts as a fluid regulator and as a safety shut-off, substantially as described.

4. In a device of the character described, 100 the combination of a burner, a vaporizing expansion tube subjected to the heat of said burner and adapted to form a passage for a fluid fuel for said burner, a distributing rod arranged axially in said tube, means carried 105 by said rod to control the flow of fuel through said tube, a chambered member connected to said tube, loose deposit-collecting members in said chambered member, and a deflector adapted to direct heat from said 110 burner to said chambered member, substantially as described.

5. In a device of the character described, the combination of a burner, a vaporizing expansion tube affording a passage for a 115 fluid fuel for said burner, a chambered member connected with said tube and forming therewith at least a portion of a conduit for a fluid fuel for said burner, a distributing rod arranged in said tube and chamber, 120 means carried by said rod to control the flow of fuel through said conduit, and a deflector adapted to direct heat from said burner to, said chambered member, substantially as described.

6. In a device of the character described, the combination of a burner, a chambered member subjected to the action of said burner, an expansion tube also subjected to the action of said burner, said chamber and 130

tube acting as a conduit for a fuel to said burner, a shouldered connection between said tube and member, a shell, a shouldered connection between said shell and the opposite end of said tube, a ported valve member having a shouldered connection with said shell, a distributing rod secured in said tube,

and a valve on said rod coöperating with the port of said valve member, substantially as described.
